GARMENT BAG

John J. St. Laurent, Chickasaw, Ala., assignor,
by mesne assignments to International Paper
Company, New York, N. Y., a corporation of
New York

Application April 5, 1940, Serial No. 328,058

1 Claim. (Cl. 206—7)

My invention relates to garment bags and the process of making the same, and more particularly to a garment bag having a centrally disposed gap through which the hook of an ordinary garment hanger may be passed.

Garment bags of the type wherein the upper end is diagonally folded leaving a central gap or opening through which the hook of the hanger may be passed are subject to the defect that they are not dustproof due primarily to the size of the gap or opening necessary to allow the hook of the hanger to pass therethrough. Attempts have been made to reinforce this gap or opening, but so far as I am aware the reinforcement does not render the garment bag dustproof.

Therefore an object of my invention is to provide a substantially dustproof garment bag with means located adjacent the gap through which the hook of a garment hanger is passed which will yield to the passage of the said hook, but which will also reassume the normal position after the passage of said hook to thereby effect a substantial closure of said gap.

Another object of my invention is to provide a device of the character stated which comprises a flat tubular body having oppositely inclined shoulder portions formed by folding and securing the corner sections of one end and a valve disposed intermediate the shoulder portions for passage of a garment hanger hook therethrough.

Another object of my invention is to provide a device of the character stated in which the valve is formed from the material of the tubular body and is automatically closeable following passage of the hook therethrough.

Another object of my invention is to provide a device of the character stated which is so formed that no changes to existing bag making machines will be necessary in order to produce the same.

Another object of my invention is to provide a device of the character stated which requires no increase in the amount of bag making material needed as compared to that heretofore used.

Further features and advantages will become more apparent from the following description and claims when taken in connection with the attached drawing in which

Fig. 1 is a plan view of the bag tube from which the bag is formed and shows details of construction of the closing flap and tab;

Fig. 2 is a similar fragmentary view showing the manner in which the diagonally disposed shoulders are formed and their relation to the closing means; and

Figs. 3, 4 and 5 are fragmentary plan views of

the top portion of the garment bag illustrating the manner in which the hook of the garment hanger is thrust through the gap between the diagonally disposed shoulders, and the operation 5 of the closing flap.

Referring to the drawing in detail, the invention, as illustrated in the drawing, is embodied in a garment bag comprising a bag tube 10 formed in the usual manner from a continuous web of 10 paper. The tube is made by overlapping the longitudinal marginal edges 11 and 12 of the web and securing them together by adhesive. Individual bag blanks A are formed from the tube by 15 passing the tube through any suitable or conventional cut-off mechanism which will provide a projecting flap 14 as an integral part of one wall portion of the tube and preferably extending across the full width thereof, and a tab 13 centrally disposed on the other wall portion and 20 projecting coextensively with the flap. The cut-off operation will also provide a recess 13A at the other end of the blank which is complementary to the tab 13. The exact contour or configuration of the flap 14 may be changed or varied at 25 will so long as the flap 14 has a greater width than the opposing tab 13. By cutting off the bag lengths in this manner there will be no waste of material nor will there be any more material used than is used in making the conventional garment bag.

The upper corners 15 of the bag blank or form A are diagonally folded along the lines 16 in the manner illustrated in Fig. 2 to thereby provide shoulders 16 conforming generally to the contour 30 of the garment hanger. The diagonal folds are so formed as to leave a slight gap 17 therebetween. However, due to the presence of the tab 13, this gap is substantially closed. The diagonal folds are secured to the face of the bag by means 35 of spaced adhesive stripes 18 which are normally applied to the inner face of the flap 14 opposing the tab 13, but leaving a clear area or void directly opposite the tab. In order to permit displacement of the material of the flap 14 which has 40 also been folded over when the diagonal folds were made, the lines of adhesive do not extend up as far as the lateral limits 19 of the tab. The clear area opposite the tab 13 has been provided to permit displacement of the material of the flap 14 during passage of a hanger hook through 45 the gap 17 without having to displace or separate any adhered portions of material. It should be noted that the shape of the tab 13 as illustrated in the drawing is such that when the folds 16 are effected there will be no fold of any portions 50

of the tab material. This results in only a double ply rather than a triple ply as would be the case if the tab 13 were more extensive. Of course if it were found desirable to utilize an additional thickness a more extensive tab 13 may be employed.

By reference to Figs. 3 and 4 of the drawing, it will be observed that a garment hanger 20, having a hook 21 connected therewith by a shank portion 22, is so disposed within the bag that the hook 21 is being pushed through the gap 17. It should be noted that the material of the flap 14, being free to move, has been displaced an amount sufficient to allow passage of the hook. Further movement of the hook will position the shank portion 22 thereof within the gap 17 and the normal resiliency of the paper of the blank will cause the flap 14 to return to the normal folded position, thereby substantially closing the gap opened by the passage of the hook. (See Fig. 5.) In this manner the top of the bag is closed so that it is substantially dustproof from the top.

In garment bags generally it is the custom to leave the bottoms thereof open for ready insertion of garments therein. However, if after a garment has been placed within the bag, it becomes desirable to close the lower end thereof, such closing may be effected by any conventional means such as by turning up the bottom and securing it in such position or by actually sealing the bottom with adhesive or the like.

Thus it will be observed that the invention herein described provides a substantially dustproof garment bag which comprises a flat tubular body having oppositely inclined shoulder portions formed by folding and securing the corner sections of one end and having valve means dis-

posed intermediate the said inclined shoulder portions for permitting passage of a garment hanger hook therethrough and being automatically closeable following passage of the hook.

Many methods of constructing the above described garment bag may be employed and I do not therefore wish to be limited to any particular type of machine. As will be appreciated by those skilled in the art, little or no change need be made to existing bag making machines since the formation of the tab 13 can be done by merely adjusting the cut-off means, and the paste applying device can be notched so as not to apply paste to the tab.

I claim:

A garment bag comprising a flat tubular body including opposed wall portions, one of said wall portions being provided with a flap projecting beyond the end of the other wall portion, said other wall portion being provided with a centrally disposed upwardly tapering tab of less width than said flap and of a length equal to that of the flap, adhesive applied to the inner surface of said flap in spaced strips, the void between said spaced strips of adhesive being disposed generally opposite said tab, the upper corners of said tubular body being folded over onto the wall portion that includes said tab along lines substantially meeting at the top, the sides of said tab substantially coinciding with the fold lines to thereby provide oppositely inclined shoulder portions, said flap and said tab conjointly forming a central valve for passage of a garment hanger hook and being automatically closeable following passage of the hook therethrough.

JOHN J. ST. LAURENT.
